UNITED STATES PATENT OFFICE.

ALFRED G. CAMPBELL, OF SHERBROOKE, QUEBEC, CANADA.

RAILWAY FOOT-GUARD.

SPECIFICATION forming part of Letters Patent No. 423,511, dated March 18, 1890.

Application filed June 15, 1889. Serial No. 314,327. (No model.)

To all whom it may concern:

Be it known that I, ALFRED G. CAMPBELL, a citizen of Canada, residing at Sherbrooke, in the county of Sherbrooke and Province of Quebec, Canada, have invented a new and useful Railway-Frog Guard, of which the following is a specification.

It is well known that many persons have met with serious and often fatal injuries by having caught a foot in a railway-frog and being unable to remove it before being run over by an approaching train.

The object of my invention is to remove this danger by providing a railway-frog with guards in such a manner that it will be impossible for the foot of any person to be caught therein. I attain this object by the mechanism illustrated in the accompanying drawings, in which—

Figure 1 is a perspective view of a railway-frog, showing the guard in position against the side of the rail; and Fig. 2, a cross-section of the rails and guards, showing the method of fastening the guard to the rail.

Similar letters refer to similar parts throughout the several views.

In the accompanying drawings, A is the rail, and B the guard, which is fastened to its side. The guard B is a thin casting of iron, which is beveled at the ends to fit the various angles of the frog. As the rails are likely to vary slightly in size and shape, the guard B is made thin on its upper edge, and is provided on the side next the rail with two bosses d and e, so that it may fit any rail. Both said bosses slope inwardly toward the rail A, so that whatever the height of the rail may be the upper boss d will form a shoulder against the upper flange of the rail, and the lower boss e will

form a shoulder against the lower flange of the rail. This result might be obtained by making the guard B thicker and shaping it to the rail A; but it would be much heavier, and therefore more cumbersome and expensive, than if cast as shown. The upper edge of the guard B is brought to a thin edge, so that it may come well up to the top of the rail A, and still not interfere with the flanges of the car-wheels.

To fasten the guard B to the rail A a hole is bored through the guard and through the

web of the rail. A bolt c, provided with a suitable head and nut, is inserted in the hole and drawn up tightly, thus fastening the guard firmly against the rail.

55

The guard B may be made with the outside entirely smooth or with the lower part corrugated, as shown in the accompanying drawings. When the guard B is corrugated and the rails are near together, it may be fastened by a T-spike t, the spike being driven into a tie between the rails and each arm of the spike entering the corrugations of the guard of each rail. (See Fig. 2.) The lower edge of the guard B is provided with grooves or notches, as shown, to afford space for the spikes with which the rails are fastened to the ties. As the rail A is wider at the bottom than at the top, when the guard B is fastened against it, the guard will form an inclined plane slanting toward the rail. I prefer to make the guard B of malleable iron, so that when a rail is winged or curved, as shown in Fig. 1, the guard may be bent to fit it. This is necessary to keep the guard out of the way of the car-wheels.

70

When the foot of any person is caught in a railway-frog, it is because the rails are near together or approach each other, and the foot is slipped between the flanges of the rails, and in making efforts to remove it the foot is frequently pressed more firmly between the rails; but with my invention it will be seen that the sides of the rails facing each other will present two smooth surfaces, or surfaces smooth except for the slight vertical corrugations, slanting or flaring outwardly as they approach the top of the rail, and between which it will be impossible for the foot to be caught.

85

I am aware that heretofore guards for the inside of rails have been used, such being the subject of patent to Hart, No. 240,587, dated April 26, 1881. I therefore do not claim such, broadly, as my invention; but

90

What I claim, and desire to secure by Letters Patent, is—

1. As a new article of manufacture, the guard B, having the bosses d and e, and means, as bolts c, for fastening said guard to the rail A, substantially as described, and for the purpose set forth.

95

100

2. The railway-frog guard B, having its upper edge thin, as shown, and having means, as the bosses *d* and *e*, to adapt it to the size and shape of the rail A, substantially as described.
- 5 3. The guard B, having its lower portion corrugated, as shown, in combination with means, as bolt *t*, for fastening said guard to the rail A, substantially as described.
4. The combination, in a railway-frog guard, 10 of the guard B, having its lower portion corrugated and grooved, as shown, with the bolt

t and rail A, substantially as shown and described.

5. The guard B, provided with bosses *d* and *e* and having its lower portion grooved and 15 corrugated, as shown, in combination with means, as bolt *t*, for fastening said guard to the rail A, substantially as described.

ALFRED G. CAMPBELL.
